UNITED STATES PATENT OFFICE

2,309,444

VEGETABLE SLICER

Ralph P. De Vault, Arcadia, Calif.

Application July 29, 1941, Serial No. 404,553

8 Claims. (Cl. 30—280)

My invention relates to a slicer, especially adapted for the slicing of vegetables, but being also useful for the slicing of food stuffs and other products of a character to be cut by a knife.

It is an object of the invention to provide a slicer having as a feature self-adjustment of the cutting knife, due to the provision of a pivoted cutter having a knife and a guide bar in parallel relation. An especial feature of the invention is that the cutter and its supporting handle are so formed and related that the cutting action may be carried down to the surface on which the article to be sliced is supported.

It is an object of the invention to provide a slicer having a pivoted cutter of simple form wherein the cutting edge is at least as low as any other part of the cutter, so that no other part of the cutter will project beyond or below the cutting edge, thereby making it possible during the cutting operation to bring the knife edge into engagement with the surface of a cutting board on which the article being sliced is supported during the slicing operation.

It is also an object of the invention to provide for a slicer a cutter having at least one end thereof so formed that no metal part at such end will project below the cutting plane defined by the cutting edge, thereby making it possible to bring the cutting edge, or at least a major portion thereof, into contact with the surface of a cutting board.

A further object of the invention is to provide a cutter adapted to slice an article along planes which are diagonally disposed with relation to the cutting board on which the article to be sliced is supported. The formation of the cutter is such that as each diagonal cut is completed, the cutting edge will pass into engagement with the surface of the cutting board, thereby severing the completed slice from the article from which the slice has been cut.

An object of the invention is to provide a slicer which, due to its pivoted cutter, may be rapidly operated, which will quickly cut slices diagonally from the article to be sliced, or which may be employed with facility to cut slices parallel to the upper face of the cutting board on which the article to be sliced rests.

A further object of the invention is to provide a slicing cutter and a simple handle in cooperation therewith, the cutter and the handle being so formed that they may be readily separated, thereby making it possible to quickly detach the cutter from the handle, and also making possible the provision of a set of cutters for slices of different thicknesses, with a single handle by which the cutters may be selectively employed.

Further objects and advantages of the invention will be brought out in the following part of the specification.

Referring to the drawing which is for illustrative purposes only:

Fig. 1 is a plan view of a preferred form of my slicer.

Fig. 2 is a perspective view showing a manner in which the slicer may be employed for diagonal cutting.

Fig. 3 is a fragmentary section taken on the plane represented by the line 3—3 of Fig. 1.

Fig. 4 is a sectional view similar to Fig. 3, but with the supporting arm or fork removed.

Fig. 5 is a sectional view similar to Fig. 4, but showing the blade of the cutter before grinding.

Fig. 6 is a fragmentary sectional view showing the manner in which the diagonal cut is made.

Fig. 7 is a fragmentary sectional view showing the position of the cutter for making a slice parallel to a surface.

Fig. 8 is a longitudinally sectioned view showing a form of my slicer wherein the slicing cutter is supported by a handle disposed at one end of the cutter.

Fig. 9 is a sectional view of a cutter having both of its parallel bars sharpened.

The preferred embodiment of my invention, as shown in Fig. 1, comprises a cutter 10 which is preferably stamped as a pair of parallel bars 11 and 12 connected by end members 13 which lie in planes which are perpendicular to the plane defined by the members 11 and 12. One of the members 11 or 12 has its inner edge sharpened so as to form a cutting edge along the slot 14 which separates the members 11 and 12. The remaining bar or member will serve as a guide bar for the knife during the cutting operation. It is recognized that both of the members 11 and 12 may be sharpened so as to form knife edges, but during the use of one member 11 or 12 for a cutting operation, the remaining member serves as a guide bar to ride ahead of the cutting edge upon the surface of the article which is being sliced.

As shown in Fig. 4, each end member 13 has a hole 16 disposed between the cutting edge 15 of the knife 11 and the inner edge of the guide bar 12. This hole, however, is closer to the knife edge 15 than to the inner edge of the bar 12. A handle 17 is provided having forks 18, the ends 19 of which curve downwardly and at their extremities have pivot pins 20 which project outwardly through the openings 16 in the end members 13 of the cutter 10. The handle 17 may be bent from flat metal stock to the form shown. The forks 18 have sufficient flexibility that they may be deflected toward each other from the position in which they are shown in Fig. 1, so as to disengage the pivot pins 20 from the openings 16. It is, therefore, possible to conveniently disengage the cutter 10 from the handle 17, and in the practice of my invention I may provide several cutters 10 having slots 14 of different

sizes and blades and guide bars 11 and 12 arranged to cut slices of different thicknesses. For example, a set of three cutters might be provided ranging in size from $\frac{1}{8}$ " to $\frac{3}{16}$ ", or larger as may be found desirable.

From Fig. 4, it will be noted that the knife 11 and the guide bar 12 are disposed in planes arranged angularly to each other, in the general arrangement of a wide-angled V form. Likewise, the lower edges of the member 13 lie in the planes defined by the lower faces of the knife 11 of the guide bar 12. In view of this, the lower edge of each end member 13 has a corner or sharp bend 21 disposed in such position that the opening 16 lies between the cutting edge 15 and this corner 21, and between the corner 21 and the cutting edge 15 the end member 13 has a flattened portion 22, lying in a plane with the lower face of the knife 11. Accordingly, if the cutter 10, as shown in Fig. 3, is moved into engagement with a flat surface 23, the point of application of pressure through the pivot pins 20 to the end members 13, lying between the shoulders 21 of the end members 13 and the outer edge of the knife 11, will result in the rotation of the cutter 10 so as to bring the knife edge 15 into engagement with the surface 23, so that the cutting plane of the knife 11 will coincide with the surface 23. It will be noted that no portion of the cutter 10 projects beyond (or below) the cutting plane of the knife 11, which cutting plane is represented by the surface 23.

The formation of the cutter 10 contributes to ease in grinding the knife 11 so as to provide a sharp cutting edge. Since no portion of the cutter projects below the cutting plane, as explained in the foregoing paragraph, the cutters 10 may be moved consecutively and continuously across a grinding wheel, so that the grinding operation will extend from end to end of the cutter, without the necessity of starting the grinding at a point spaced from one end of the cutter and then discontinuing the grinding operation before the other end of the cutter is reached. The cutter 10, prior to the sharpening thereof, has the appearance shown in Fig. 5. The knife 11 has a cross sectional area comprising a relatively flat rectangle. In the grinding operation all metal lying below the plane G—G is removed, thereby changing the form of the cutter 11 from rectangular cross-section to triangular cross-section and forming the cutting edge 15 shown in Fig. 4. Also, it will be noted that this grinding operation removes that portion 24 of each end member 13 lying below the plane G—G.

The slicer is adapted for different types of slicing operations, and is so constructed that these slicing operations may be conducted with ease and relative speed. In Fig. 2 I show one manner in which the slicer may be employed in conjunction with a cutting board 25 to diagonally cut slices 26 from an article or articles. In the present instance, a number of string beans 27 are shown upon the upper surface of the cutting board 25, with the cutter 10 of the slicer at the start of a cut. If the article to be cut is held with one hand upon the upper surface of the cutting board 25, the cutting operation by use of the slicer may be started at one end of the article, and diagonal slices may be cut progressively therefrom. When the cutter 10 travels rightward from the position in which it is shown in Fig. 2, it will move diagonally downward until the cutter 10 engages the upper surface of the

cutting board 25, and as the end of the cut is reached, the cutter 10 will automatically adjust itself into such position, as shown in Fig. 6, that the knife edge 15 will engage the upper surface 5 of the cutting board, and in so doing will pass out of cutting engagement with the article from which the slices are being cut.

In the fragmentary view, Fig. 7, the cutter 10 is shown positioned for the start of a slicing cut parallel to the surface 28 of an article 29. When force is applied to move the cutter 10 rightward from the position in which it is shown in Fig. 7, the knife 11 will follow the dotted line 30 and remove a slice having the thickness which 15 is characteristic of the cutter 10 employed.

A feature of the invention is to provide a slicer so formed that its pivoted cutter may be brought into engagement with a flat surface, such as the surface of a cutting board, and to carry out this 20 conception it is only necessary that one of the end members 10 of the cutter be so formed that it will not project below the cutting plane of the knife. This condition is true for the reason that one end of the cutter may be allowed to project 25 over the edge of the cutting board. For example, in Fig. 8 I show a cutter identified by the numeral 10', for the reason that it is so formed that a handle 32 may be connected to one end thereof, but has the characteristics described relative to 30 the cutter 10 in that the cutting edge 15, its knife 11, and its guide bar 12 are so formed relative to the end members 13a and 13b that the cutting edge 15 may be brought into engagement with the surface 33 of a cutting board 34. When the 35 slicer, shown in Fig. 8, is employed, it may at times assume a position wherein a portion of its knife 11 projects over the edge 35 of the cutting board 34. The end member 13b is formed so as to provide a tube 36 in which the end of a shaft 37 40 is secured, this shaft 37 being turnably supported by the handle 32, whereby adjusting rotation of the cutter 10' is permitted.

In Fig. 9 I show a cross-section of cutter 10b having bars 11b and 12b, both of which are sharpened so as to provide cutting edges. In this 45 form of the invention it is preferable to place the pivot opening 16b equidistant from the bars 11b and 12b. In this cutter the end member 13b is so formed that no portion thereof projects 50 below the cutting plane of the cutter. In the operation of this cutter, either one of the bars may be employed as a knife, while the remaining bar rides ahead and serves as a gauge or guide.

I claim as my invention:

- 55 1. In a hand operated slicer of the character described, the combination of: a handle; a slicing cutter comprising a pair of coextensive bars and end members connecting adjacent ends of said bars to hold the same in such relation that at least one of the bars may have its inner edge sharpened so that it will serve as a knife while the remaining bar serves as a guide to move ahead of said knife during a slicing operation, said end members being so formed that no portion thereof projects below the cutting plane of the cutter; a pair of spaced arms extending from said handle to points contiguous to said end members and with the extremities thereof formed so that no portion thereof projects below the cutting plane of the cutter; and means pivotally connecting said end members and said arms so that said cutter may have adjusting rotation relative to said handle on an axis substantially parallel and close to said knife.
- 60 2. In a hand operated slicer of the character

described, the combination of: a handle; a slicing cutter comprising a pair of coextensive bars and end members connecting adjacent ends of said bars to hold the same in such relation that at least one of the bars may have its inner edge sharpened so that it will serve as a knife while the remaining bar serves as a guide to move ahead of said knife during a slicing operation, and said end members being so formed that no portion thereof projects below the cutting plane of the cutter; and means pivotally connecting said cutter and said handle so that said cutter may have adjusting rotation relative to said handle on an axis parallel and close to said knife said means comprising a support extending from said handle to said cutter, the extremity of said support engaging at least one of said end members and said extremity being positioned so that no portion thereof projects below the cutting plane of said cutter.

3. In a hand operated slicer of the character described, the combination of: a handle; a slicing cutter comprising a pair of coextensive bars and end members connecting adjacent ends of said bars to hold the same in such relation that at least one of the bars may have its inner edge sharpened so that it will serve as a knife while the remaining bar serves as a guide to move ahead of said knife during a slicing operation, said end members each being so formed as to provide a downwardly faced shoulder spaced from said knife in the direction of said guide and so that no portion thereof projects below the cutting plane of the cutter; and means pivotally connecting said cutter and said handle so that said cutter may have adjusting rotation relative to said handle on an axis substantially parallel and close to said knife and offset from said shoulder in the direction of said knife.

4. In a hand operated slicer of the character described, the combination of: a handle; a slicing cutter comprising a pair of coextensive bars and end members connecting adjacent ends of said bars to hold the same in such relation that at least one of the bars may have its inner edge sharpened so that it will serve as a knife while the remaining bar serves as a guide to move ahead of said knife during a slicing operation, at least one of said end members being so formed as to provide a downwardly faced shoulder spaced from said knife in the direction of said guide and so that no portion thereof projects below the cutting plane of the cutter; and means pivotally connecting said cutter and said handle so that said cutter may have adjusting rotation relative to said handle on an axis substantially parallel and close to said knife and offset from said shoulder in the direction of said knife.

5. In a hand operated slicer of the character described, the combination of: a handle having a pair of spaced arms supported for relative movement toward and away from each other; a slicing cutter comprising a pair of coextensive bars and end members connecting adjacent ends of said bars to hold the same in such relation that at least one of the bars may have its inner edge sharpened so that it will serve as a knife while the remaining bar serves as a guide to move ahead of said knife during a slicing operation, at least one of said end members being so formed as to provide a downwardly faced shoulder spaced

from said knife in the direction of said guide and so that no portion thereof projects below the cutting plane of the cutter; and means engageable and disengageable by said relative movement of said supporting arms pivotally connecting said end members and said supporting arms so that said cutter may have adjusting rotation relative to said handle on an axis substantially parallel and close to said knife and offset from said shoulder in the direction of said knife.

5. In a hand operated slicer of the character described, the combination of: a handle having a pair of spaced arms supported for relative movement toward and away from each other; a

15 slicing cutter comprising a pair of coextensive bars and end members connecting adjacent ends of said bars to hold the same in such relation that at least one of the bars may have its inner edge sharpened so that it will serve as a knife

20 while the remaining bar serves as a guide to move ahead of said knife during a slicing operation, at least one of said end members being so formed as to provide a downwardly faced shoulder spaced from said knife in the direction of said guide

25 and so that no portion thereof projects below the cutting plane of the cutter; and means pivotally connecting said cutter and said handle so that said cutter may have adjusting rotation relative to said handle on an axis substantially parallel and close to said knife and offset from said shoulder in the direction of said knife, said means comprising trunnions projecting outward from said arms into engagement with said end members.

30 35 7. In a hand operated slicer of the character described, the combination of: a handle having cutter supporting means; and a complement of slicing cutters comprising a plurality of cutter members, each adapted to cut a slice having a

40 thickness different from the thickness of the slice cut by another of said cutters, interchangeably pivotally connectible to said cutter supporting means, each of said cutter members comprising a pair of coextensive bars and end mem-

45 bers connecting adjacent ends of said bars to hold the same in such relation that at least one of the bars may have its inner edge sharpened so that it will serve as a knife while the remaining bar serves as a guide to move ahead

50 of said knife during a slicing operation, at least one of said end members being so formed that no portion thereof projects below the cutting plane of the cutter.

55 8. In a hand operated slicer of the character described, the combination of: a handle having spaced inwardly yieldable supporting arms; a

60 slicing cutter comprising a pair of coextensive bars and end members connecting adjacent ends of said bars to hold the same in such relation that at least one of the bars may have its inner edge sharpened so that it will serve as a knife while the remaining bar serves as a guide to move ahead of said knife during a slicing operation, said end members consisting of walls extending

65 at right angles to said bars and having openings between said bars, said end members being so formed that no portion thereof projects below the cutting plane of the cutter; and trunnions projecting outwardly from said supporting arms into said openings.

RALPH P. DE VAULT.
